ACCESSORY FOR CURTAIN DRAPES

Ovsay Lipetz, New York, N. Y.

Application February 25, 1947, Serial No. 730,711

2 Claims. (Cl. 160—124)

1

This invention relates to curtains of cloth and other material and the like, draperies or hangings for interior decorative purposes, such as curtains hung along the top of a window in a room, and tastefully arranged at the opposite sides of the window.

Curtains of this type are embellished with flounces and ruffles, particularly along the vertical edges and across the upper part, just under the hem which contains the bar or rod supporting the curtain. An important object of this invention is to provide an accessory or attachment adapted to be disposed across the top of the curtain and having a design and finish that greatly increase the ornamental effect thereof. The curtain is of course fashioned out of two or more pieces, all worked in the manner required, and sewed together, to make the curtain complete. With the accessory the style of the curtain can be modified if desired, the color scheme can be altered without loss of harmony, and the entire curtain can be made much more attractive and thus caused to assume an entirely renovated and remodeled appearance.

The desired result is attained in the manner described below, and illustrated on the drawings which show preferred forms of the invention. But this disclosure is explanatory only and I may make changes in details without departure from the principle of the invention or change in the essential characteristics thereof.

On said drawings,

Figure 1 is a front view of a curtain according to my invention.

Figure 2 is an enlarged vertical section on line 35 2—2.

Figure 3 is a front view of a part of a modified embodiment of the invention, and

Figure 4 is a vertical section through the invention as illustrated in Figure 3.

Figure 1 presents a curtain made of a piece of woven or knitted cloth, paper or other material 1, substantially rectangular in shape, and having along one vertical edge a flounce or row of ruffles 2. The opposite side 3 hangs down adjacent one vertical edge of the opening containing the window, in the usual way when the curtain is suspended along its top. It is gathered into folds toward the side 3 by a loop or "tie-back" 4 or any other means; the folds being indicated at 5. Such curtains are nearly always hung in pairs, one at each side of the opening. Along the upper edge a strip 6 to form a hem is attached to the sheet or body 1; this strip being of folded cloth with a line of stitches 7 along

the middle. Its overlying edges at the border remote from line of fold, which runs along its top as shown in Figure 2, are turned in, as indicated at 8; and secured by a row of stitches 9 passing only through the edges 8. The sheet 1 has a horizontal strip 10 forming a flounce or row of ruffles along its upper edge, and is fastened to the hem band or strip 6 by a line of stitches 11 passing through it and the ruffles on the strip 10. The stitches 7 divide the double-layer strip or band 6 into two enclosed passages 12 through the lower of which the rod supporting the curtain along the top of the window is usually passed. To cooperate with the ruffles of the strip 10 and enhance their attractive effect, the strip 6 may have vertical pleats therein running from its upper to its lower edge along the length thereof.

The chief aim of this invention is to enable the owner to impart a wholly fresh and different appearance to the curtain by means of an ornamental attachment or accessory that can be used with the curtain whenever desired. This object is gained by overlaying the hem band 6 with a 20 separate valance or flounce indicated at 14, which is joined to the front layer of the strip 6 by hooks 15 on its rear face or any other suitable fastening means. It can easily be added and taken off at will. This accessory is made of another strip or band 16, folded along the middle thereof with its edges flush and having secured over it along the one edge 17 a wide band or strip 18, having gathered portions or rows of ruffles 19 and 20 along its two edges. The other edge 21 of the strip 16, which is even with the edge 17 is turned over inward. Between the edges 17 and 21 is the edge of another strip 22, which is flat and even and acts as a shadow panel. The band 6, the front layer 18 with its two lines of ruffles 19 and 20, and the back layer 22 are all 30 united by a double row of stitches 23 passing through all three parts named. The hooks or fasteners 15 are made fast on the rear layer or fold of the strip 16, near the top.

To put this accessory into place, one has only to lay it across the hem band or strip 6 of the curtain and engage the fasteners 15 with the band 6. The accessory then will extend across the full width of the curtain at the top, and its ruffles and other ornamental features will completely conceal the strip 10 at the top of the sheet 1, and whatever pleats the strip 6 may contain. The curtain then will look like a new curtain taking the place of the first one; and 40 enables the owner to bring about a virtual change

of this type of decoration without getting new curtains or taking down and altering the old ones.

This result is especially appreciable when the owner desires not only a change of pattern but also a change of color. The attachment comprising the front layer 18 with the ruffles 19 and 20 and the flat back layer 22 can be of a different hue from the sheet 1 and hem 6. If the curtain 1 is white or any other bright hue, the attachment can be green, blue, red etc., and when put into position the whiteness of the band 6 and upper part of the sheet 1 is altogether hidden under the two layers of the strip 16 and the two layers 18 and 22. The back layer 22 serves as a shadow panel, presenting the right background for whatever color the attachment has different from that which the curtain and its top hem originally present. The renovated curtain thus looks different in both style and coloring and gives the appearance of an entirely new and separate article. All these advantages are gained at little extra expense.

Figures 3 and 4 present a modification in which the accessory is made of one double strip 24 with hooks 15 or the like along the back, and the front layer gathered into pleats 25. These pleats may be box pleats or have some other shape. This strip is as wide as the combined strips 16 and 18 in Figures 1 and 2; and the pleats 25 are of a length nearly equal to the width of the strip 24 and take the place of the ruffles 19 and 20.

The accessory can of course be utilized with all kinds of curtains, such as those hung over dressing tables and other articles of furniture as well as doorways, windows and the like locations.

The invention thus has decided merit and by means of it old curtains can be made to look altogether new simply by "dressing" them and setting them off with the attachment above described.

Having described my invention, what I believe to be new is:

1. An accessory for a curtain adapted to overlie and be fastened to the upper part and extend along the width of the curtain, said accessory

30
35
40
45

comprising a longitudinally folded strip with substantially flush lower edges, one only of which is turned in, a strip forming a back layer having one edge between the two edges of said folded strip, a strip forming a front layer making contact with the other edge of the folded strip on the outer side of the latter, said front layer having ruffles along its top and bottom, stitching passing through the two layers and the two edges of the folded strip to hold the parts together, and fastening means carried by the folded strip above the inturned edge thereof.

2. The combination of a curtain and a strip adapted to overlie and be fastened to the upper part of said curtain and extend along the width thereof, said curtain having a hem along its top, said strip comprising a folded band with substantially flush longitudinal lower edges one only of which is inturned, a strip forming a back layer fastened to the band with one edge between the edges of said band, another strip forming a front layer having portions gathered into ruffles, and attached to the outer side of the folded band along the other edge, said ruffles overlapping the edges of said band, stitching to secure said band and said strips together, and fasteners attached to the band above the inturned edge, said strips covering the hem of the curtain and giving a different appearance thereto.

OV SAY LIPETZ.
